STRIP-COLLAPSING DEVICE FOR
SEWING MACHINES

James E. Ackerman, Devon, Conn., assignor to
The Singer Manufacturing Company, Elizabeth,
N. J., a corporation of New Jersey

Application March 27, 1951, Serial No. 217,835

9 Claims. (Cl. 112—136)

1

This invention relates to attachments for sewing machines and more particularly to improvements in sewing machine attachments of the strip-collapsing type.

In the production of seams in which a reinforcing fabric strip is included, as for instance, the seam between the bib and trousers portion of an overall or similar garment, it is desirable that the reinforcing strip be severed short of the edge of the garment at each side so that a neater side hem may be formed in which the reinforcing strip is not included.

Strip-collapsing devices, of which the present invention is an improvement, include those devices which are operative at the will of the sewing machine operator usually by means of an actuating linkage carried by the sewing machine to urge each side of the reinforcing strip to a position out of the line of securing stitches, thereby eliminating the tedious and time consuming necessity for removing stitches before severing the reinforcing strip short of the garment edge.

It is an object of this invention to provide a strip-collapsing device associated with the work-guiding devices as a unitary assembly, which is constructed so as to be applied to and removed from a sewing machine in a manner far more convenient than existing devices of this nature.

It is a further object to provide a unitary strip-collapsing device of the above removable and replaceable nature in combination with an actuating mechanism carried by the sewing machine frame, the parts of the strip-collapsing device and the actuating mechanism arranged in a novel fashion so as to provide a separable connection therebetween which is effective upon positioning of the unitary strip-collapsing device on the sewing machine.

Still another object of this invention is to provide in an actuating linkage for a strip-collapsing device of the above character a means for adjusting the extent or stroke of strip collapsing movement at each side of the strip and at the same time retaining the arrangement whereby the connection between the strip-collapsing device and the actuating linkage will be effective upon positioning of the unitary strip-collapsing device on the sewing machine regardless of the position of adjustment of the actuating linkage.

With these and other objects in view, as will hereinafter appear, the invention comprises the devices, combinations and arrangements of parts described in connection with the accompanying

2

drawings, which illustrate a preferred embodiment and in which:

Fig. 1 is a front elevational view of a portion of a sewing machine having my invention applied thereto,

Fig. 2 is a fragmentary sectional view taken substantially along line 2—2 of Fig. 1,

Fig. 3 represents a bottom plan view of the unitary strip-collapsing device,

Fig. 4 represents a fragmentary side elevation of a portion of the actuating linkage, viewed as in Fig. 1 but illustrating a modified form of the adjustable connection,

Fig. 5 represents a top plan view of a portion of the sewing machine having my invention applied thereto and in which parts have been broken away to more clearly illustrate the invention,

Fig. 6 is a sectional view of part of the invention taken substantially along line 6—6 of Fig. 5, showing the manner in which the strip collapsing members are supported and arranged with respect to the slide-plate,

Fig. 7 represents a perspective view of the strip collapsing fingers and the connection between the strip collapsing fingers and the actuating linkage showing particularly the relation of these parts with respect to the fabrics being stitched which are illustrated in dot-dash lines, and

Fig. 8 is a fragmentary elevational view of the delivery end of the attachment and the strip collapsing members with the work-pieces in section, showing, in full lines, the facing strip in normally extended condition and, in dotted lines, the strip-collapsing members in strip-collapsing position with the facing strip gathered between them so as to be confined in a space less than the needle gauge of the sewing machine.

In the selected embodiment illustrated in the drawings, the invention is shown as applied to a sewing machine of the type having a frame including a bed 10 of which the upper surface forms a work support 11. A standard 12 rises from the bed and supports an overhanging bracket-arm 14 from the extremity of which a presser-foot 15 is suspended and a needle bar 16 is journaled for reciprocatory motion. Needles 17 carried by the needle bar cooperate with the complementary lower stitch forming mechanism (not shown) arranged beneath the work support in the formation of stitches. The needles also cooperate with feed dogs 18 which are operative through slots 19 in a throat plate 20 to advance the work past the stitching point. The work support 11 is formed with an opening 21 in advance

of the stitching point which provides access to the lower stitch forming mechanism as, for instance, for threading the loopers in the case of the illustrated chain stitch sewing machine, or for bobbin replacement if a lockstitch machine were to be used.

As shown most clearly in Figs. 2 and 5, work guiding devices for forming a seam including a reinforcing strip, together with a mechanism for collapsing the strip, are supported as a unitary assembly from a slide-plate 22 which is provided with spring clips 23-23 adapted to embrace the work support 11 at the sides of the opening 21 to frictionally maintain the slide-plate in the access opening.

Overlying the slide-plate 22 is a sheet metal covering plate 24 which is arranged in spaced relation to the slide-plate by means of a spacing block 25; both the covering plate and the spacing block being secured in place on the slide-plate 22 as by soldering, brazing, etc. On the upper surface of the covering plate, an edge guide 26 is secured by means of fastening screws 27-27. To the edge guide 26, in turn, an edge folding guide 28 is secured by means of screws 29-29. As best shown in Fig. 8, the edge guide and the edge folding guide are arranged to direct the marginal edges of two panels, A and B, respectively, of body fabrics which are to be stitched together so as to form a reinforced seam.

Fig. 8 also illustrates in full lines the relative positions of a reinforcing strip S as it is normally delivered from a tubular strip guide 30 which is formed at its delivery end with scrolls 31-31 in order to inturn the marginal raw edges of the strip. To accommodate the strip-guide in an upwardly inclined position beneath the slide-plate 22, the slide-plate is provided on each side at its forward extremity with downturned ears 32-32, to which is secured by fastening screws 33-33 a U-shaped guide-supporting yoke member 34. The strip-guide 30 between its ends is provided with laterally extending ears 35-35 by which the guide is secured to the yoke member by the screws 36-36. The slide-plate 22 at its forward edge is recessed, as at 37, to accommodate the delivery end of the strip-guide.

In the normal operation of the body fabric guides and reinforcing strip guide as described above, the fabrics are directed to the stitching point in the relationship as illustrated in the dot-dash lines of Fig. 7. With special regard to the reinforcing strip, it will be noted that the inturned edge portions normally are directed each to the path of one or more needles. When in a subsequent operation, the reinforcing strip must be severed short of the edge of a garment, it is advantageous that the strip be free of the stitches from the point at which it is severed to the edge of the garment, because if not, these stitches must be removed by a tedious and time consuming hand operation.

In the present invention, a new and improved construction is provided for at will shifting or "collapsing" the strip at a point between the delivery end of the strip-guide and the needles, to a sidewise gathered position in which the strip will be excluded from the lines of stitches being formed. To this end, opposed strip-engaging members, indicated generally as 38 and 38', each of the opposite hand, are arranged in the space between the slide-plate 22 and the sheet metal covering plate 24 and are adapted to be manually shifted so that they relatively approach each other and thereby collapse the strips between

them. A detailed description of one of the strip-engaging members will suffice, since the comparable opposing members are identical and merely reversed in position. In the drawings, the base numbers, generally 38 through 51, apply to parts of the right hand strip-engaging members as viewed in Fig. 1, while the prime numbers refer to comparable parts of the left hand strip-engaging member.

The strip-engaging member 38 comprises a flat base-plate 39 which is disposed to underlie the slide-plate 22. A rectangular slide-block 40 extends upwardly from the plate 39 and is adapted to enter a guide-slot 41 formed in the slide-plate 22 which confines the slide-block for translatory movement laterally of the strip guide 30. The flat base-plate 39 is formed with an ear 42 to which is secured a wire spring 43 that is held in place on the slide-plate 22 by a screw 44. The spring 43 biases the strip-engaging members 38-38' apart into what is termed a normal retracted position, a position determined by the ends of the guide slot 41 in the slide-plate 22.

Carried above the slide-plate 22 is a U-shaped member 45 of which one limb 46 is slotted as at 47 to accommodate fastening screws 48-48 by which the U-shaped member is secured to the slide-block 40 for convenient lateral adjustment to a wide range of retracted positions to accommodate a variety of strip widths or bodily shifting of the strip.

As clearly illustrated in Fig. 6, the limb 46 of the U-shaped member 45 and the base-plate 39 extend beyond opposite sides of the slide-block 40 so as to lock the strip-collapsing mechanism in place on the slide-plate 22. The free end of the U-shaped member 45 is formed with a laterally extending finger 49 which is disposed between the delivery end of the strip-guide 30 and the needles 11. The free extremity of the finger 49 is shouldered to provide a vertical strip-engaging surface 50 and a flat overhanging extension 51. The leading edge of the vertical strip engaging surface 50 is beveled as at 52 to permit smooth passage of the strip past the fingers.

In usual practice and as illustrated clearly in Fig. 7, the strip-engaging members are adjusted by means of screws 60-63 so that when in normal retracted position the strip-engaging surface 50 just clears the edge of the strip as it emerges from the strip-guide. In this position, it will be appreciated that the strip-engaging members present no obstruction nor do they hinder initial insertion of the strip in any manner.

The means by which the above described right and left hand strip-engaging members 38 and 38' may be moved simultaneously into operative position will now be described. As illustrated in Fig. 1, the actuating means comprises generally a linkage carried by the bed 10 and including a lever 100 fulcrumed by the pivot screw 53 which secures the lever to the bed. At one side of the screw 53, a longitudinally slidable bar 54 is pivotally connected to the lever by a pin 55. A second longitudinally slidable bar 56 is pivotally connected to the lever at the opposite side of the fulcrum by a pivot-pin 57. The slide-bar 56 and the pivot-pin connection 57 with the lever are constructed in a novel manner as will be described below to permit a particularly advantageous adjustment of the relative movements imparted by the linkage.

In order that the strip-engaging members and the other parts carried by the slide-plate may be conveniently removed and replaced, readily sep-

arable connections are provided between the slide-bar 54 and the strip-engaging member 38 and between the slide-bar 56 and member 38'. The separable connections each comprise complementary coupling means arranged to interengage in positive driving connection when the slide-plate 22 is properly positioned in the access opening of the work-plate. Referring particularly to Fig. 7, the base-plate 39 of the right hand strip-engaging member 38 is formed with a short extension 58 to which is fixed a rod 59 which extends laterally through a guide notch 60 formed in the downturned ear 32 of the slide-plate. The rod 59 is formed at its free extremity with spaced shoulders 61 and 62 to provide one part of the separable coupling with the slide-bar 54. Secured to the bar 54 by means of a fastening screw 63 and a locating pin 64 is a coupling member 65 having outwardly extending jaw members 66 and 67 defining an opening or notch 68 which is adapted to engage the rod 59 between the spaced shoulders 61 and 62 when in operative position. The free extremity of each jaw member is inclined as at 69 so as to properly admit the rod 59 despite slight misalignment due to manufacturing tolerances etc.

The separable connection between the left hand strip-engaging member 38' and the slide-bar 56 is similar to the above described connection. Base-plate 39' is formed with a long lateral extension 70 to which is fixed a rod 71 which extends laterally through a guide notch 60' in the downturned ear 32 and is formed at its free extremity with spaced shoulders 73 and 74. The slide-bar 56 is provided with a coupling member 75 which is identical with coupling member 65 and is secured to the slide-bar 56 in the same manner. The guide notches 60 and 60' of the downturned ear 32 are closed by a notched keeper 72 secured to the downturned ear so as to slidably confine both of the rods 59 and 71 in place on the slide-plate.

It will be appreciated that the separate connections of the preferred embodiment are susceptible of modification within the spirit of the above disclosure. As an instance, the jaw members defining a notch or opening may be carried by the strip-engaging members and the complementary rod formed as part of the slide-bar.

In order for the rods 59 and 71 properly to reengage the coupling members 65 and 75, respectively, upon replacement of the slide-plate into the access opening of the work-plate, the actuating linkage is biased by a spring 76, which is arranged between the bed 10 and the lever 52, into a normal retracted position as determined by the strip block 77. In this normal retracted position, the notches 68 of the coupling members are disposed laterally coincident with the lateral position in which the shouldered extremities of the rods 59 and 71 are biased by the spring 43. In addition, a bracket 78 which is secured to the bed 10, is provided with a vertical projection 79 which is spaced from the bed to define a guide slot in which both slide-bars 54 and 56 are confined. When the slide-plate is removed, the bracket projection 79 serves to support the slide-bars so that the vertical position of the bars remains substantially the same. The inclined surfaces 69 of the jaws being sufficient to accommodate a reintroduction of the rods 59 and 71 despite any slight change of vertical position of the jaws. A connection between the lever 100 and a foot treadle or a knee shifter device or the like may be made in any desired fashion; a rod 80 is

illustrated in Fig. 1 for this purpose. A stop member 81 adjustably secured to the bed 10 limits the operative movement of the lever 100 in response to actuation by the rod 80. As the lever 5 is turned, the slide-bars 54 and 56 will be moved in opposite directions and by means of the coupling connection will impart simultaneous strip-collapsing movements to the opposed strip-engaging members.

In the specific embodiment illustrated in the drawings, it will be noted that three needles are employed, and as shown in Fig. 7, two of the needles are arranged to penetrate the left hand edge of the reinforcing strip while a single needle is disposed so as to penetrate the right hand edge. It necessarily follows, therefore, that the left hand strip-engaging member 38' must be moved a greater distance than the right hand member 38 in order for both edges of the strip to be moved into needle avoiding position. As illustrated in Fig. 1, the position of the pin 55 which connects bar 54 to the lever 100 is disposed nearer the pivot screw 53 of the lever than the connection of the bar 56 with the lever. It will be apparent therefore that the stroke of bar 56 will exceed that of bar 54 in proportion to the difference in distance between the lever connections therewith and the pivotal axis of the lever.

30 It is frequently desirable to change the stroke of one or both of the strip-engaging members, as for instance, if the number of needles at either side of the strip is changed. The instant construction provides such an adjustment of stroke in a novel and advantageous manner such that the extreme position of the parts remains unchanged. To this end, a link 82 is interposed between the lever 100 and the bar 56. A clamp screw 83 connects the link with the bar and may be tightened to secure the link in any desired fixed angular position with respect to the bar. It will be apparent, therefore, that the link 82 when so clamped forms with the bar 56 in effect a single solid connection between the pivot-pin 57 and the coupling member 75. A slot 84 is formed in the lever to accommodate a pivotal connection 57 with link 82. Fig. 4 illustrates a construction in which the slot 84 is arcuate, the center of curvature corresponding to the axis of the clamp screw 83 when the bar 56 is disposed in normal retracted position. It will be appreciated that with such an arcuate slot, a full range of adjustment of the link is possible without disturbing the spring biased extreme position of the bars 54 and 56.

In a modified form of construction illustrated in Fig. 1, the slot 84 is straight; however, it is formed along a line tangent to the arc formed by movement of the pivotal connection 57 about the axis of the clamp screw 83; in other words, the straight slot of Fig. 1 is formed to closely approximate the arcuate slot of Fig. 4. The straight slot is preferable for manufacturing economy and it is pointed out that, since the straight slot is tangent to the ultimately desired arc, only a slight shifting of the bar 56 is involved, this being compensated for by the inclined surfaces 69 of the jaws.

Having thus set forth the nature of the invention, what I claim herein is:

1. A strip-collapsing attachment for sewing machines comprising a supporting plate, means securing said supporting plate to said sewing machine for ready removal and replacement, work-guides including a strip-guide carried by

said supporting plate, said plate having elongated slots formed therein transversely of said strip-guide, a pair of slide-blocks arranged in said slots, a strip-engaging member secured at one side of each of said blocks, actuating mechanism carried by said sewing machine for imparting strip collapsing movements to said strip-engaging members, and means secured at the opposite side of each of said blocks disposed in operative relation with said actuating mechanism when said supporting plate is replaced on said sewing machine.

2. In a sewing machine having a frame including a work-support with an access opening therein, a strip-collapsing attachment comprising a cover-plate removably secured on said work-support in said access opening, work-guiding means including a strip-guide carried by said cover-plate, said cover-plate having an elongated slot formed therein transversely of said strip-guide, two slide-members disposed at one side of said cover-plate, said members each being formed with a slide-block disposed to enter said transverse cover-plate slot, opposed strip-engaging members each secured to one of said slide-blocks at the opposite side of said cover-plate from said slide-members, and means carried by said sewing machine frame for at will moving said slide-members in opposite directions.

3. In a strip-collapsing device for sewing machines, a work-guiding attachment including strip-guiding means, a strip-guide supporting member, and movable strip-collapsing members carried by said strip-guide supporting member, said attachment constructed for ready removal and replacement on said sewing machine, a mechanism carried by said sewing machine for imparting movement to said strip-collapsing members, complemental coupling means formed on said strip-collapsing members and on said actuating mechanism, said coupling means disengageable upon removal of said attachment from the sewing machine and constructed and arranged to provide effective driving connection between each of said strip-collapsing members and said actuating mechanism when said work-guiding attachment is positioned on said sewing machine.

4. In a strip-collapsing device for sewing machines, a work-guiding attachment including strip-guiding means, a strip-guide supporting member, opposed strip-collapsing members carried by said strip-guide supporting member for transulatory movement transversely of said strip-guide, and a first spring means biasing said strip-collapsing members into normal retracted positions, said attachment being constructed for ready removal from and replacement on said sewing machine, a linkage carried by said sewing machine for imparting movement to said strip-collapsing members in opposite directions, a second spring means biasing said linkage into normal retracted position, each of said strip-collapsing members and said actuating linkage being formed with complemental coupling surfaces to provide readily separable connections therebetween, said coupling surfaces being disposed to reengage upon replacement of said attachment on the sewing machine.

5. In a strip-collapsing device for sewing machines, a work-guiding attachment including strip-guiding means, a strip-guide supporting member, opposed strip-collapsing members carried by said strip-guide supporting member for

translatory movement transversely of said strip-guide and a first spring means biasing said strip-collapsing members into normal retracted positions, said attachment being constructed for ready removal from and replacement on said sewing machine, a linkage carried by said sewing machine for imparting movement to said strip-collapsing members in opposite directions, a second spring means biasing said linkage into normal retracted position, each of said strip-collapsing members and said actuating linkage being formed with complemental coupling surfaces to provide readily separable connections therebetween, one of said complemental coupling surfaces of each separable connection comprising a projection, and the other of said coupling surfaces defining an opening arranged to accommodate said projection.

6. In a strip-guiding device for sewing machines, strip-guiding means, at least one movable strip-engaging member arranged at each side of said strip-guiding means, said strip-engaging members each having a stroke from normal retracted position out of the path of said strip to a strip-collapsing position in the normal path of said strip, and an actuating mechanism for said strip-collapsing members, including a lever pivotally secured to said sewing machine, separate slide-bars disposed to transmit motion from said lever to each of said strip-engaging members, a link arranged between one of said slide-bars and said lever, clamp means adjustably securing said link to said slide-bar, a guideway formed on said lever, a guide element carried by said link and adapted to secure said link pivotally to said lever along said guideway at any selected one of a range of distances from the pivotal support of said lever to permit an independent adjustment of the stroke of one of said strip-engaging members without disturbing said normal retracted position thereof.

7. In a sewing machine having stitch-forming instrumentalities and work-guiding devices for producing a seam including a reinforcing strip, and means for at will collapsing said strip into a stitch-avoiding position, said mechanism including a pair of movable strip-engaging members disposed in normal retracted positions one at each side of said reinforcing strip, and a linkage carried by said sewing machine for at will shifting said strip-engaging members into strip-collapsing positions in the normal path of the reinforcing strip, said linkage including two lengthwise shiftable bars each connected at one end to a respective one of said strip-engaging members, and a lever pivotally carried by said sewing machine and provided with a connection with each of said bars to impart operative movement to said bars in opposite directions, one of said bars having a joint formed intermediate its ends, said joint having an axis about which the end portions of said bar may be angularly positioned, the connection between said jointed bar and said lever being adjustable to vary the strip-collapsing position of one of said strip-engaging members without changing the normal retracted position thereof, said connection including a pivot-pin carried by said bar, an arcuate slot formed in said lever to adjustably accommodate said pivot-pin, the center of curvature of said arcuate slot corresponding with the axis of said bar joint when said strip-engaging members are disposed in normal retracted positions.

8. A device as set forth in claim 7, in which said lever is provided with a straight slot, said

slot being arranged along a line which is tangent to the arc formed by movement of said pivot-pin about the axis of said bar joint when said strip-engaging members are disposed in normal retracted positions.

9. In a sewing machine having stitch-forming instrumentalities and a work-support formed with an aperture providing access to said stitch-forming instrumentalities and adapted to accommodate a slide-cover plate, a strip-collapsing device including strip-guiding means, a strip-guide supporting plate interchangeably replaceable with the slide-cover plate in said work-support aperture, a pair of strip-engaging members slidably secured to said strip-guide supporting plate, 15 means associated with said supporting plate confining said strip-engaging members for translatory movement transversely of said strip-guide, and actuating mechanism carried by said sewing machine for imparting strip-collapsing movements to said strip-engaging members, said mechanism including a pair of spaced members slidably secured to said sewing machine, and a linkage connecting said members for movement in

5
10

opposite directions, and complementary coupling means providing an interlock between each of said strip-engaging members and a respective one of said actuating members, each of said coupling means comprising a projection extending from one of said members, the other of said members being formed with an apertured portion arranged to accommodate said projection when said attachment is slidably introduced in place in the work-support aperture of the sewing machine.

JAMES E. ACKERMAN.
